UNITED STATES PATENT OFFICE

BJARNE H. SCHIELDROP, OF LONDON, ENGLAND, ASSIGNOR TO BLAW KNOX COMPANY,
OF PITTSBURGH, PENNSYLVANIA, A CORPORATION OF NEW JERSEY

APPARATUS FOR PROJECTING MATERIALS

Original application filed September 29, 1927, Serial No. 222,740. Divided and this application filed May 21, 1928. Serial No. 279,305.

My invention relates to projecting apparatus for loose or plastic materials, and particularly to a curved tool for insertion into the trajectory of material discharged from the machine for directing the material into places normally inaccessible to the projecting machine. The present application is a division of my co-pending application Serial No. 222,740, filed Sept. 29, 1927.

For supplying loose or plastic materials to inaccessible locations, I have provided a projecting machine in which material is fed from a bin onto an endless conveyor moving with sufficient velocity to throw or project a stream 15 of loose material from the endless conveyor when the direction of movement of the endless conveyor suddenly changes. An example of the use for such a machine is found in the application of repair material, such as 20 dolomite, to the interior of heated furnaces for restoring the surfaces of the fire walls of the furnaces. The machine is carried on a truck and is adapted for rotation about a turn table. Provision is also made for raising or lowering the direction of the stream 25 of discharged material. Such a machine is shown and described in my co-pending application.

The stream of projected material normally 30 passes through an opening in a furnace wall and the area accessible to such material is defined by the size of the opening and the trajectory of the material passing through the opening. In all such cases however, the 35 inner wall immediately adjacent the opening is inaccessible to material traversing the opening. Where it is necessary to repair the inaccessible portions of the furnace wall it has heretofore been necessary to permit the 40 furnace to cool sufficiently for a workman to enter the furnace and apply the loose or plastic material. As the value of certain of the materials increases when they are applied to a hot surface, it is desirable that the repair 45 material be applied to the normally inaccessible portions of the wall at the highest possible temperature of the wall.

I provide a tool in the form of a spoon insertible through the opening in the wall and 50 into the trajectory of the discharged material.

By manipulating the spoon it is possible to deflect the projected material and throw it against the inner wall of a furnace or other structure which is otherwise inaccessible to material projected through an opening in the 55 wall.

The accompanying drawings illustrate the present preferred embodiment of the invention, in which;

Figure 1 is a plan view of a projecting 60 machine for loose or plastic material, in combination with a deflecting tool or spoon, and

Figure 2 is a perspective view of a deflecting tool or spoon embodying my invention.

Referring to Figure 1, a projecting apparatus for loose or plastic materials comprises in general a truck 2 on which is mounted a motor 4 and gear train 5 for driving the truck, together with a projecting machine 6 for directing a stream of loose or plastic materials 7 to a desired location. The projecting machine 6 comprises a motor-driven endless conveyor 8. Material is fed to the conveyor from a bin 9 through a gate 10. The details of the endless conveyor 8, bin 9 and gate 10 are 75 described in my co-pending application, and do not constitute an essential part of the invention claimed in the present application, except in so far as they are necessary for an 80 understanding of that invention.

The projecting machine 6 is rotatable about a turn table comprising a track 11, by a handle 12. The handle 12 comprises a telescoping section 14 connected to the gate 10 for actuating the latter by a turning movement; 85 and a section 15 connected by a swivel coupling 16 to the section 14 and extending into the machine 6 for turning the machine about the track 11, and for raising or lowering the direction of the stream of the projected material, as described in my co-pending application. A machine for projecting a stream of material is also shown in my Patent No. 1,576,366, dated March 9, 1926.

The stream 7 of projected material is directed through an opening 17 in a wall 18. The wall 18 may constitute one of the walls of a furnace wherein it is desired to replenish surfaces of the walls. By adjusting the position of the truck 2 and the angular position 95 100

of the projecting machine 6 thereon, it is possible to direct the stream 7 against a large part of the furnace walls. Where the stream of projecting material 7 is dolomite, it is advantageous that it be applied to the furnace walls while the furnace walls are still hot. Difficulty has heretofore been experienced in applying the stream to the inner face of the wall 18 adjacent the opening 17.

10 For applying the stream of material to the inner surface of the wall 18 adjacent the opening 17, I provide a tool 19 in the form of a spoon insertible through the opening 17 and into the trajectory of the stream 7. The rear wall 20 of the spoon is curved and by manipulating the angles of incidence and reflection of the stream 7 against the curved rear wall 20, it is possible to direct the stream 7 against a large part of the inner surface of the wall 18, which surface is normally inaccessible to material being discharged from the endless conveyor 8.

15 A handle 21 is attached to the rear wall 20 and terminates in a grip 22. The length of the handle 21 is made sufficiently long to be supported by a rest 24 on the frame of the truck 2. However, it is to be understood that the spoon may be removed from the support 24 if desired. Arcuate side walls 25 are 20 provided on the spoon which taper toward the outer or discharge end 26 thereof for concentrating the material deflected by the spoon. The inner end 27 of the spoon is left open in order to provide free access of the projected material to the curved surface 20. By rotating the spoon 19 about the axis of the stream 7, it is possible to deflect a portion of the stream 7 over substantially the entire inner area of the wall 18.

25 40 While I have shown and described the present preferred embodiment of my invention, it is to be understood that it may be otherwise embodied without departing from the spirit of the invention and the scope of the appended claims.

I claim:

1. A tool for intercepting a stream of moving material and deflecting the material to a place normally inaccessible to the stream of material, comprising a curved wall portion, arcuate side walls extending generally toward the center of curvature from the curved wall portion, and a handle attached thereto.

50 55 2. A tool for intercepting a stream of moving material and deflecting the material to a place normally inaccessible to the stream of material, comprising a tapering curved rear wall, flanges extending inwardly from the rear wall for defining a channel, and a handle secured to the outer surface of said rear wall.

60 65 3. A tool for intercepting a stream of moving material and deflecting the material to a place normally inaccessible to the stream of material, comprising a tapering curved

70 rear wall, flanges extending inwardly from the rear wall for defining a channel, and a handle secured thereto, said handle having a length sufficiently great to permit the insertion of the curved wall and flanges through an opening in a furnace while permitting an operator to remain at a safe distance from the furnace.

75 4. A tool for intercepting and deflecting a stream of moving material comprising a curved and tapering channel portion open at both ends, and an elongated handle secured to the outer convex surface of said channel portion;

80 85 5. A deflecting tool comprising a longitudinally curved channel having a deflecting surface for deflecting material directed thereagainst, and a handle connected thereto and disposed entirely in a position offset with respect to such surface and such surface extended.

90 In testimony whereof I have hereunto set my hand.

BJARNE HAIER SCHIELDROP.
